UNITED STATES PATENT OFFICE.

THADDEUS F. BAILY AND FRANK T. COPE, OF ALLIANCE, OHIO, ASSIGNEES TO THE ELECTRIC FURNACE COMPANY, OF ALLIANCE, OHIO, A CORPORATION OF OHIO.

REGENERATIVE FURNACE.

1,286,907.

Specification of Letters Patent.

Patented Dec. 10, 1918.

Application filed January 25, 1918. Serial No. 213,631.

To all whom it may concern:

Be it known that we, THADDEUS F. BAILY and FRANK T. COPE, citizens of the United States, both residing at Alliance, in the county of Stark and State of Ohio, have invented a new and useful Regenerative Furnace, of which the following is a specification.

This invention relates to electric furnaces and has more especial reference to a regenerative furnace adapted to be operated at low temperature for the treatment of small articles.

The object of the invention is the provision of a low temperature regenerative furnace designed for the efficient and economic heat treatment of small articles.

A further object is the provision of a furnace of this character with means for passing the articles to be heat treated into and out of the furnace.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

In the accompanying drawings:

Figure 1 is a sectional plan view taken on the line 1—1, Fig. 2.

Fig. 2 is a section on the line 2—2, Fig. 1.

Fig. 3 is a section on the line 3—3, Fig. 1.

Fig. 4 is a view similar to Fig. 1 showing another adaptation of the furnace.

Fig. 5 is a section on the line 5—5, Fig. 4.

Similar numerals of reference indicate corresponding parts throughout the several figures of the drawing.

Referring more especially to the construction illustrated in the accompanying drawings, the numeral 1 indicates the heating chamber of the furnace which is preferably formed of fire brick or other suitable heat resisting material and which communicates with the reduced hood 2, also formed of heat resisting material such as fire brick or the

like, said hood being of any length desired or necessary for the particular kind of work for which it is to be used.

55

The object of the said hood will be to prevent the escape of the heat into the outside atmosphere from the train of material leaving the furnace, which train is to be more fully hereinafter described. The heat thus inclosed will be absorbed by the train of material entering the furnace, also to be herein-after more fully described. Thus a regenerative operation takes place by the use of the hood and for this reason the hood may be 60 specifically described as a regenerative hood.

Extending entirely through the heating chamber and regenerative hood and projecting through the door 3 at the usual extremity of said hood is a bed 4 formed of suitable heat resisting material and supported at intervals upon the spaced walls 5 which

70

walls also support the resistance troughs 6 which are located within the heating chamber and at each side of the bed 4 said resistance troughs carrying the resistance material and electrodes 7. Each trough consists preferably of the lower wall 8 and the upright sills 9 formed of fire brick or other suitable material. Each of these troughs is 80 filled with a resistance body consisting of a carbonaceous material in granular form such as crushed coke, charcoal or the like, said carbonaceous material being designated in the drawings by the numeral 10. The 85 electrodes 7 are embedded in the resistance material, preferably near each extremity of each trough, said electrodes extending through the furnace walls as shown in the drawings. It will be understood that the 90 electrodes 7 should be arranged in an electric circuit, such construction being well known in this art. Electric wires 11 are shown connected to each of the electrodes 7, said wires leading to a suitable source of 95 electricity. When the current is supplied to the electrodes it will be conducted from one electrode to the other through the resistance material, thus raising the said resistance material to an intense heat. It will of course 100 be understood that gas or other heating means may be provided in the heating chamber instead of the electric means above described.

100

Located above the table 4 and spaced therefrom is a second table 12 which terminates within the heating chamber at a point spaced from the inner end of the table 5 4 as indicated at 13. Suitable means is provided for pushing the material to be heat treated through the door 3 upon the upper table 12 and for pushing the material out of the furnace from the other extremity 10 thereof. For the purpose of illustration a pusher is shown at each extremity of the furnace operated by a fluid cylinder, the pusher 14 being operated by a fluid cylinder 15 and arranged to push the articles to be 15 treated in the furnace designated by the letter A through the door 3 and into the regenerative hood upon the upper table 12. As each new article is placed in position at the door 3 and the pusher operated it 20 will be seen that all of the articles ahead thereof upon the table 12 will be moved forward, the foremost of said articles being pushed from the table 12 at the inner extremity thereof and allowed to drop upon 25 the lower table 4 as indicated at B. As the pusher 16 is operated by means of the fluid cylinder 17 the articles which have thus dropped upon the table 4 are pushed to the back through the regenerative hood and are 30 ejected one at a time through the door 3 thereof from where they may be removed. As shown in Fig. 3 a casing 18 may be provided around the furnace for the purpose of retaining the heat within the walls of 35 said furnace.

It will be seen from the above description and inspection of the drawings that with this construction a furnace is provided which is especially adapted for operation at 40 a low temperature for the heat treatment of small articles which could not be conveniently handled in the ordinary manner.

Referring to the construction illustrated in Figs. 4 and 5 of the drawings, a slight 45 modification is shown in these figures, means being provided for passing two trains of material through the regenerative hood and furnace in the same horizontal plane and for transferring material from one train to 50 the other after it has passed through the regenerative hood and heating chamber and for passing this treated material back out of the heating chamber and through the regenerative hood.

55 In this construction the heating chamber 19 is formed in the usual manner and provided with the resistance elements 20 located at each side thereof, the regenerative hood 21 communicating with the heating 60 chamber and being of any desired length. Provided at the opposite extremity of the heating chamber is a small reduced portion 22 within which the transferring of material from one train to the other takes place.

65 Located through the entire length of the

furnace is a table 23 upon which the material is moved, said table being located between the resistance elements 20 as shown in the drawings. Suitable means is provided for pushing the material to be heat treated through the regenerative hood and heating chamber upon the table 23, for transferring the material to the outgoing train and for pushing the material out of the furnace from the other extremity thereof, after the same has been subjected to the heat treatment and transferred to the outgoing train. For the purpose of illustration a pusher operated by a fluid cylinder is shown at each extremity of the furnace 80 and in the reduced portion 22 by transferring the material. The pusher 24 is operated by a fluid cylinder 25 and arranged to push the articles to be heat treated in the furnace designated by the letter C through 85 the regenerative hood and heating chamber upon the table 23, as each new article is placed in position upon the table 23 at the open end of the regenerative hood, the pusher 24 is operated, moving said article 90 and all of the articles ahead thereof in the incoming train forward, the foremost of said articles being moved to the position indicated by the letter B. As the pusher 26 is operated by means of the fluid cylinder 95 27, the article indicated by the letter D will be moved transversely across the table 23 to the outgoing train and as the pusher 28 is operated by means of the fluid cylinder 29, the articles in the outgoing train are pushed step by step back through the heating chamber and the regenerative hood and are rejected one at a time from the open end of the regenerative hood from where they may be removed.

105 We claim:

1. A furnace comprising a heating chamber and a regenerative hood and means for passing a continuous train of material through the furnace and heating chamber 110 and back through the regenerative hood.

2. A furnace comprising a heating chamber and a regenerative hood and two trains of material moving in two parallel directions through said furnace, one of said 115 trains of material being located above the other and means for dropping material from the upper to the lower train.

3. A furnace comprising a heating chamber and a regenerative hood, means for passing material through the regenerative hood and heating chamber and dropping the material to a lower plane and means for pushing the material out through the heating chamber and regenerative hood in said 120 lower plane.

4. A furnace comprising a heating chamber and a regenerative hood, a pair of spaced tables located in different vertical planes, means for pushing material into the furnace 125 130

upon the upper table and means for pushing the material out of the furnace upon the lower table.

5. A furnace comprising a heating chamber and a regenerative hood, a pair of spaced tables located in different vertical planes within said furnace, the upper table terminating within said heating chamber short of the lower table, means for pushing ma-

terial to be treated into the furnace upon the upper table and on to the lower table and means for pushing the material out of the furnace upon the lower table.

In testimony that we claim the above, we have hereunto subscribed our names.

THADDEUS F. BAILY.
FRANK T. COPE.
